INVENTOR

Norris Elmore Clark,

N. E. Clark
ATTORNEY

UNITED STATES PATENT OFFICE.

NORRIS ELMORE CLARK, OF PLAINVILLE, CONNECTICUT, ASSIGNOR TO ROBERT S. ALLYN, TRUSTEE.

EXPANDED-METAL REINFORCEMENT.

1,309,242.

Specification of Letters Patent.

Patented July 8, 1919.

Original application filed March 2, 1909, Serial No. 480,796. Divided and this application filed February 12, 1915. Serial No. 7,759.

To all whom it may concern:

Be it known that I, NORRIS ELMORE CLARK, a citizen of the United States of America, and residing at Plainville, in the county of 5 Hartford and State of Connecticut, have invented new and useful Improvements in Expanded-Metal Reinforcements, of which the following is a specification.

This invention relates particularly to expanded metal fabrics having ribbed, corrugated or grooved beams, tension members or ribs. These beam members are preferably relatively deep and comparatively narrow. The expanded meshwork portion forms a 15 lathing substantially all in one plane and the beam members project from this plane.

The main object of my invention is to improve a fabric of this character so that the beams will be capable of affording the 20 maximum reinforcement. Another object is to provide means for securing lathing or other reinforcing members to the beams or for fastening the beams to other elements.

According to the preferred form of the 25 invention the beams are provided with relatively small perforations or indentations in their sides between the front and rear edges so as to permit plaster or cement to pass through and be interlocked from one side to the other. I also may provide fingers secured to the sides of the beams for the attachment of lathing or other purposes. These fingers may be formed by cutting portions from the sides of the beam members 30

35 and bending them outwardly. The beam members provide reinforcement in one direction and substantially all of the rigidity at right angles to the beams is afforded by the expanded meshwork in ordinary fabrics of this character. I propose to reinforce the fabric at right angles to the beams by means of rods or other members secured to the beams at intervals. These rods may be passed through holes punched in the sides of 40 the beams so that they practically become a part of the fabric. As the beams are relatively deep and narrow, these rods passing through holes in the beams prevent the sides of the beams from spreading. The rods also 45 connect adjacent beams and thus prevent them from separating or approaching each other. Adjacent sheets of the fabric with their beams overlapped or interlocked, as is

common, may also be locked together by these rods passing through the beams. 55

Figure 1, illustrates fragments of a fabric embodying my invention and having holes in the beams, rods extending through some of these holes and also attaching fingers.

Fig. 2, is a side view showing one of the 60 beams with the holes in the sides and also attaching fingers.

Fig. 3, is a sectional view of the fabric of Fig. 1 showing a transverse reinforcing rod extending through the beams and showing 65 a section of lathing attached to the beams by means of fingers.

Fig. 4, is a sectional view of a fabric showing holes in the beams and attaching fingers.

Figs. 5, 6 and 7 are sectional views of 70 three different forms of beams with holes in the sides.

The expanded meshwork may be of any suitable character and provided with the beams such as 11, 11 of suitable cross section, 75 preferably relatively deep and narrow and open at 12 at the face adjacent the expanded meshwork and closed at 13 at the folded edges or apices. The sides of the beams in the form shown are perforated as at 14, 15 80 and 16.

Rods such as 17 are secured to the beams, for instance, by passing the rods through holes such as 14 either at the time of manufacture or at the place where the fabric is to 85 be used.

The fingers 18 may be formed by cutting out portions of the sides of the beams and bending the portions outwardly either at the time of manufacture or when it is desired to utilize such fingers. 90

These fingers 18 may be utilized for the attachment of additional lathing such as 19.

In the form shown in Fig. 5 the rib or beam member is formed from a special 95 rolled section having an enlargement 20 extending along the apex.

In the form shown in Fig. 6 the fabric is provided with enlarged sectional portions 21 at the base of the beam. 100

In the form shown in Fig. 7 the beam is provided with reverse flanges 22.

By having holes in the sides of the beams the plaster or cement can interlock from side to side and thus avoid the formation of lines 105 of cleavage in the cement or plaster along

the apices of the beams. The beams thus give great transverse stiffness without danger of fracture. Some advantage is had by indenting the sides so as to form recesses 5 instead of having holes passed entirely through the beams.

By having at least some of the perforations in the different beams in line with each other, fastening clips, wires and devices or 10 transverse reinforcing rods may be readily inserted. The transverse rods not only hold the sides of the beams together but prevent the different beams from separating from or approaching each other. These rods also 15 prevent the beams from tipping over or tilting. This is of especial importance in the erection of the fabric when the beams and meshwork are not reinforced by the presence of the cement or plaster. When forming 20 roofs it is customary to place boards on top of the fabric and utilize it as a flooring for the workmen and the transportation of materials. This brings great strain to bear upon the fabric. The transverse rods connected to the beams as above described prevent any failure of the fabric from the presence of this additional load.

The projecting fingers may be utilized for attachment purposes for instance, the attachment of other sheets or lathing. The 30 spacing between the fingers will depend upon how rigid the connection of the lath or other member must be.

The interlocking of the cement or plaster 35 in the holes, recesses or indentations in the sides of the beams increases the bonding effect and prevents longitudinal slipping movement of the beams.

The member 19 is positively locked to the 40 beams by the fingers 18 and thus helps to hold the beams in their proper positions.

The rods 17 passing through the beams reinforce the fabric to withstand pressure from both faces.

This application is a division from 45 #480,976, filed March 2nd, 1909, now Patent 1,128,659.

What I claim is:—

1. Reinforcing material for cementitious 50 constructions comprising, a plurality of expanded metal sections and a plurality of parallel relatively deep, non-expanded channel-like beam members having transversely extending side walls, the expanded sections 55 integrally connecting the walls of the beam members and rods extending substantially at right angles to the beam members and across the expanded sections, opposite faces of each rod engaging the opposite walls of the beam 60 members to reinforce the expanded fabric at right angles to its plane and to limit opening out of the channel-like beam members by strains in the plane of the fabric at right angles to the beam members.

65 2. An expanded reinforcing structure

comprising, a plurality of non-expanded double-walled beam members open at one edge and expanded sections integrally connecting the edges of the beam members and means for connecting the opposite walls of 70 each beam member at intervals to limit the spreading of its walls.

3. In a fabric of the character described, a plurality of expanded metal sections integrally connected by relatively deep, non- 75 expanded, channel-shaped beam members, and a transverse stiffening member passing through said beam members in a plane substantially parallel to the plane of the expanded metal sections, thereby tending to 80 maintain all the expanded metal sections in a common plane.

4. A metallic fabric comprising parallel, unexpanded relatively deep, channel-like beam members and meshwork connecting 85 said beam members, said beam members consisting of folded unslotted strips in channel-like form with their sides extending in planes substantially transverse to the general plane 90 of the meshwork, the front and rear edges of said beam members being continuous, unbroken and imperforate for affording material tensile resistance and the sides of said beam members between the front and rear edges being provided with bonding 95 means to anchor the sides of the beams and prevent the formation of lines of cleavage in the cement along the closed edges of the beams, said meshwork consisting of a plurality of strands connected to form a plurality 100 of relatively small openings.

5. A composite building construction comprising expanded metal sections in one plane, folded ribs between the expanded metal sections and integral therewith, an expanded 105 metal sheet in a plane parallel with said first mentioned plane, and fingers integral with said ribs and securing said expanded metal sheet to said ribs.

6. A composite building construction comprising expanded metal sections in one plane, folded ribs between the expanded metal sections and integral therewith, an expanded metal sheet in a plane parallel with said first mentioned plane, fingers integral with 110 said ribs and securing said expanded metal sheet to said ribs and rods extending transversely through said ribs between the planes of the expanded metal sections and the expanded metal sheet respectively.

7. An expanded metal sheet having an unexpanded rib integral therewith, metal attaching members formed by punching holes in the rib and bending said members outwardly and a second expanded metal sheet 115 secured to the rib of the first sheet by means of said attaching members.

8. A composite building construction comprising an expanded metal fabric having reinforcing ribs projecting from the reticu- 120 125 130

lated portion thereof, said ribs having projecting fingers integral therewith and a sheet of lath secured to said fabric by said fingers.

9. A building material comprising an expanded metal fabric having unexpanded ribs projecting from the reticulated portion, said ribs having projecting fingers and a second

sheet of fabric secured to the first by means of said fingers.
